UNITED STATES PATENT OFFICE.

JAMES M. HILLARD, OF GULFPORT, MISSISSIPPI, ASSIGNOR OF ONE-HALF TO M. W. CONNOR, OF COLUMBIA, MISSISSIPPI.

TURPENTINE-EXTRACTOR.

1,103,878.

Specification of Letters Patent. Patented July 14, 1914.

Application filed January 11, 1913. Serial No. 741,491.

To all whom it may concern:

Be it known that I, JAMES M. HILLARD, a citizen of the United States, residing at Gulfport, in the county of Harrison and State of Mississippi, have invented new and useful Improvements in Turpentine Extractors, of which the following is a specification.

This invention relates to a turpentine retort or extractor, and one of its objects is to provide a retort for extracting turpentine and by-products from wood which may be conveniently charged and quickly and conveniently emptied of the refuse at the end of the extracting operation.

A further object of the invention is to provide a retort or extractor having means for circulating steam through the mass of wood, and for agitating and feeding the wood in such manner as to insure the rapid and thorough distribution of the steam therethrough and the extraction of the constituents of the wood.

The invention consists of the features of construction, combination and arrangement of parts hereinafter fully described and claimed, reference being had to the accompanying drawings, in which:

Figure 1 is a vertical longitudinal section through an extractor constructed in accordance with my invention. Fig. 2 is a horizontal transverse section on the line 2—2 of Fig. 1. Fig. 3 is a similar view on the line 3—3 of Fig. 1.

Referring to the drawing, 1 designates the cylindrical body of the extractor, which is provided with a removable frusto-conical base portion 2, the proximate edges of said body and base portion being provided with flanges for the passage of securing bolts 3, whereby they are detachably connected. The extractor is supported by a suitable frame or stand 4, and has at its upper end an outlet 5 for the passage of the vapors to a suitable condenser. At the top and one side of the retort is also a charging inlet 6 communicating with a feed pipe or chute 7 leading from a conveyer 8, whereby the material to be treated may be conveyed to the extractor from a hog or storage room. A door 9 is provided for closing the charging inlet during the operation of the extractor.

The frusto-conical base 2 is provided with an inverted frusto-conical screen 10, the

opening in which is normally closed by a screen 11 carried by a dumping door 12. This door 12 is provided with a flange 13 secured to a flange 14 at the lower end of the base portion 2 by bolts 15. The door 12 has a depressed portion forming a collection space 16 provided with a valved drain outlet 17 for the tar and other heavier products, which may be drawn off into a suitable receptacle. The door is adapted, when all except one of the bolts are removed, to be swung outwardly and laterally to uncover the opening in the portion 2 and permit of the discharge of the refuse wood pulp into a receptacle 18, from which a conveyer may carry the same to a suitable point of discharge.

The retort body 1 is closed at its upper end by a head 19 to which are secured bearing and stuffing boxes 20, and arranged within the bottom 2 is a spider or cross piece 21 provided with bearings 22. A pair of vertically disposed shafts 23 and 24 is arranged within the cylinder on opposite sides of its longitudinal center, said shafts being journaled for rotation in the respective pairs of upper and lower bearings 20 and 22. The lower ends of the shafts extend down through the screen 11 and upon the exterior of the screen 11 into the collection space or chamber 25 formed by said screens, and into which the tar freed from the wood gravitates and thence passes into the collection space 16 for discharge. The shafts are suitably closed at their upper ends, but are open at their lower ends for the inlet of steam and are provided at intervals throughout their length with ports 26 for the injection of the steam into the mass of wood. Carried by the shafts are agitators 27 and 28, whereby when said shafts are rotated the material will be kept thoroughly loosened up for the passage of steam therethrough. One of the agitators is in the form of a worm adapted to communicate an upward feed motion to the wood, while the other agitator is in the form of a worm adapted to communicate downward motion to the wood, whereby both a circular and up and down motion will be transmitted to loosen up the wood in the most efficient manner and insure the thorough exposure of all portions of the wood to the action of the steam.

A valve steam supply pipe 29, leading

from a boiler or other steam generator, communicates with the collection space 25 and keeps the same heated to maintain the wood tar in a liquid condition for free discharge. The steam, from this pipe also passes up through the screen into the body of the extractor and through the hollow shafts 23 and 24, through the ports 26 of which it discharges throughout the area of the mass of wood. The turpentine and other volatile constituents of the wood are therefore rapidly and thoroughly driven off and discharged through the outlet 5 to the condenser, while the tar and other heavier by-products are freed and kept in a liquid state and gravitate downward for discharge. The upper ends of the shafts 23 and 24 carry gears 30 and 31, which mesh with a pinion 32 on a shaft 33, which also carries a beveled gear 34 receiving motion from a beveled pinion 35 on a drive shaft 36 provided with a pulley 37 or other means for receiving power from any suitable source.

In operation, it will be understood that the dumping door 12 and valve in the outlet 5 are closed, while the door 9 is opened and the chute 7 adjusted for the admission of the wood to be treated, into the extractor. When the extractor is fully charged, the chute is removed and the door 9 closed, after which the valve in the pipe 29 is opened for the supply of steam to the extractor, while at the same time the shaft 36 is set in motion to rotate the steam injecting and wood agitating pipes, the operation of which will be apparent from the foregoing description. It will be seen that as the mass of wood is kept thoroughly agitated, while steam is circulated throughout the same, the turpentine and other constituents will be quickly driven off and a complete extraction of all the turpentine and by-products capable of extraction effected. At the end of the extracting operation, the heavier by-products are driven off, the supply of steam cut off, and

the door 12 released and swung open for the discharge of the refuse, the agitators being meanwhile kept in action so that all the refuse wood will be loosened up and discharged. Hence it will be understood that the retort 50 may be quickly charged and as quickly discharged of its contents with a minimum expenditure of time and labor.

I claim:—

1. An extractor of the character described 55 comprising a retort having a vapor outlet at its upper end and a refuse outlet at its lower end, means at the latter named end for the discharge of the heavier products, vertically disposed hollow shafts within the retort 60 provided with steam discharge ports and spiral agitators, and means for simultaneously rotating said shafts in opposite directions.

2. An extractor of the character described 65 comprising a retort having a vapor outlet at its upper end and a refuse outlet at its lower end, an annular screen in said retort above said refuse outlet, a door for closing the refuse outlet provided with an outlet for the by-products and having a screen to project into the opening of the first named screen when the door is closed, said screens forming a steam chest, a steam supply pipe opening into said chest, a pair of vertically 75 disposed hollow shafts communicating at their lower ends with the steam chest and provided at intervals with steam discharge ports, spiral agitator blades mounted upon the shafts, and means for reversely rotating 80 said shafts so that one agitator blade will impart an upward motion to the material and the other agitator blade, a downward motion to the material.

In testimony whereof I affix my signature 85 in presence of two witnesses.

JAMES M. HILLARD.
